CLAIM

The ornamental design for a splattering fender for frypan, as shown and described.

DESCRIPTION

FIG. 1 is a perspective view of a first embodiment of a splattering fender for frypan, showing the new design; FIG. 2 is a front elevational view of the splattering fender for frypan of FIG. 1, a rear elevational view thereof is a mirror view of the front view; FIG. 3 is a left side elevational view of the splattering fender for frypan of FIG. 1; FIG. 4 is a right side elevational view of the splattering fender for frypan of FIG. 1; FIG. 5 is a top plan view of the for splattering fender for frypan of FIG. 1; FIG. 6 is a bottom plan view of the splattering fender for frypan of FIG. 1; FIG. 7 is a cross-section view of the splattering fender for frypan of FIG. 1 along an imaginary line VII-VII, showing contours thereof; and FIG. 8 is a perspective view of the splattering fender for frypan of FIG. 1, wherein it is used with a frypan. FIG. 9 is a perspective view of a second embodiment of a splattering fender for frypan, showing the new design; FIG. 10 is a front elevational view of the splattering fender for frypan of FIG. 9, a rear elevational view thereof is a mirror view of the front elevational view; FIG. 11 is a left side elevational view of the splattering fender for frypan of FIG. 9; FIG. 12 is a right side elevational view of the splattering fender for frypan of FIG. 9; FIG. 13 is a top plan view of the for splattering fender for frypan of FIG. 9; FIG. 14 is a bottom plan view of the splattering fender for frypan of FIG. 9; FIG. 15 is a cross-section view of the splattering fender for frypan of FIG. 9 along an imaginary line XV-XV, showing contours thereof; and FIG. 16 is a perspective view of the splattering fender for frypan of FIG. 9, wherein it is used with a frypan. The broken lines are employed to show either environmental structure or unclaimed portions of the splattering fender for frypan, and form no part of the claimed design.
